US00D709058S

(12) United States Design Patent
Hemesath et al.

(10) Patent No.: US D709,058 S
(45) Date of Patent: * Jul. 15, 2014

(54) CASE

(71) Applicant: Incipio Technologies, Inc., Irvine, CA (US)

(72) Inventors: Timothy Alan Hemesath, Huntington Beach, CA (US); Andy Fathollahi, Corona Del Mar, CA (US)

(73) Assignee: Incipio Technologies, Inc., Irvine, CA (US)

() Term: 14 Years

(21) Appl. No.: 29/432,914

(22) Filed: Sep. 21, 2012

(51) LOC (10) Cl. 14-03

(52) U.S. Cl.

USPC D14/250

(58) Field of Classification Search

USPC ..... D14/138 AD, 138 C, 138 G, 203.7, 230, D14/238.1, 240, 247, 248, 250, 253, 341, D14/345, 346, 439, 440, 447; D13/103, D13/107, 119; D3/201, 218, 22, 301; 206/37, 320; 220/662; 361/679.27, 361/753, 737; 455/575.1, 575.4, 575.8

(57) CLAIM

The ornamental design for a case, as shown and described.

DESCRIPTION

FIG. 1 is a front perspective view of a case showing our new design.

FIG. 2 is a rear perspective view thereof.

FIG. 3 is a front view thereof.

FIG. 4 is a rear view thereof.

FIG. 5 is a left side view thereof.

FIG. 6 is a right side view thereof.

FIG. 7 is a top end view thereof; and,

FIG. 8 is a bottom end view thereof.

The broken lines illustrate unclaimed features of the case which form no part of the claimed design.

1 Claim, 6 Drawing Sheets
